UNITED STATES PATENT OFFICE.

RUSSELL BLACK, OF HUNTINGTON, WEST VIRGINIA.

SIPHON.

Application filed September 29, 1927. Serial No. 222,856.

This invention relates to siphons and more particularly to a siphon adapted to be actuated by steam so that water will be drawn through the siphon and thereby allow the 5 siphon to be employed to remove water from a boat, caisson, barge or the like.

One object of the invention is to so form the siphon that steam passing through it will create a very strong suction in the water 10 inlet without any reaction from the steam and apply direct pressure to water passing through the outlet so that the water will be forcibly ejected from the siphon.

Another object of the invention is to form 15 the siphon as a single casting and thereby produce a siphon which will be simple in its construction and very strong and durable.

Another object of the invention is to provide a siphon which may be employed when 20 dredging a river bed and to prevent danger of clogging the siphon by having the entire inside construction of the same diameter.

The invention is illustrated in the accompanying drawing, wherein

25 Figure 1 is a longitudinal sectional view through the siphon, and

Fig. 2 is a transverse sectional view taken on the line 2—2 of Fig. 1.

The siphon is formed as a single casting 30 and consists of a body portion 1 enlarged intermediate its length, as shown at 2, and having its upper end portion formed with a longitudinally extending bore 3 which communicates with a chamber 4 formed in the enlarged intermediate portion 2 of the body. The outer end portion of the bore 3 is threaded, as shown at 5, so that an outlet pipe 6 may be screwed into the outlet end of the body and conduct water sucked through the 40 siphon to a suitable place of disposal. The chamber 4 extends circumferentially in the enlarged intermediate portion of the body about a boss 7 which extends upwardly in the chamber and terminates close to the inner end of the outlet passage 3. Its upper end portion is beveled, as shown at 8, so that steam may pass from the chamber about the boss into the outlet and cause a strong suction to take place in the passage 9 which ex-

50 tends through the body, as shown in Fig. 1, and communicates with the bore or water inlet passage 10 formed axially through the side arm 11. The side arm which is cast integral with the body projects radially therefrom and its bore or passage 10 is threaded, as shown at 12, so that a suction

hose or pipe 13 may be secured in the side arm. The pipe 13 may be of any length desired in order to reach the place from which water is to be withdrawn. Since the boss 60 which forms walls for the upper portion of the passage 9 terminates close to the lower or inner end of the passage 3 and the steam passes at a rapid rate into the passage 3 about the tapered upper end of the boss, a 65 very good suction will be formed through the passage and the water freely sucked through the pipe 13 and passage 9 and caused to pass upwardly through the passage 3 and pipe 6. In order to admit steam to the chamber 4, 70 there has been provided a passage 12 which passes through the body at the opposite side thereof from the side arm 11 and at its lower end communicates with the bore or passage 18 formed axially in the lower end portion 75 14 of the body. The walls of the passage 13 are threaded, as shown at 15, to receive a pipe 16 leading from a suitable source of steam. The steam after passing from the pipe 16 into the passage 12 enters the chamber 4 and from this chamber passes into the passage 3 thereby causing a suction in the passage 9 and bore 10 to cause a column of water to move through the pipe 13 and out of the siphon through the passage 3 and pipe 85 6. In view of the fact that the siphon is formed as a single casting, it will be simple in its construction and very strong and durable.

Having thus described the invention, I 90 claim:

1. A siphon comprising a hollow body open at its upper and lower ends and having its intermediate portion enlarged to provide a chamber having an outlet leading from its 95 upper end and a reduced inlet communicating with its lower end, and a hollow side arm extending transversely from the lower portion of the enlarged intermediate portion of said body and having an elbow at its inner 100 end extending upwardly in the chamber and terminating adjacent the upper end thereof in alignment with the outlet.

2. A siphon comprising a body increased in diameter intermediate its ends and formed 105 with a side arm adjacent the lower end of the enlarged portion, the enlarged portion having an annular chamber formed in its upper portion about a central boss and the side arm having a bore extending axially therethrough 110 and upwardly in the body through the boss, the upper end portion of the body having a

bore extending axially therethrough and communicating with the chamber above the boss to provide an outlet and the chamber having the upper portion of its walls converging upwardly and gradually merging into the outlet, and the lower end of the body having a bore extending axially through the

same and communicating with a passage extending upwardly through the body at the opposite side of the boss from the side extension and opening into the chamber. 10

In testimony whereof I affix my signature.

RUSSELL BLACK. [I. S.]
